TYPEWRITING MACHINE

Louia K. Seagrave, Middletown, Conn., assignor
to Remington Rand Inc., Buffalo, N. Y., a cor-
poration of Delaware

Application October 15, 1937, Serial No. 169,110

13 Claims. (Cl. 197—177)

My invention relates to typewriting machines, and more particularly to improvements in tabulating mechanism therefor.

In a tabulating mechanism of the column selecting type, it is customary to provide a plurality of column stops adjustably mounted in spaced relationship longitudinally of the carriage, and these column stops generally differ from each other in that each is provided with a contact portion which is so disposed as to travel in a different path from the contact portion of any of the other column stops. The cooperating or column selecting stops are usually key controlled and mounted on the frame of the machine at different heights or positions corresponding to the different paths of travel of the contact portions of the column stops on the carriage, so that each column selecting stop coacts with only one of the column stops to arrest the carriage at a given columnar field.

In certain typewriting machines, such as the No. 10 Remington Noiseless and the No. 11 Remington machines, the carriage in its entirety has a substantially vertical case shifting movement relative to the frame of the machine. In such constructions, it will be clear that the vertical case shifting movement of the column stops with the carriage will interfere with the proper selective cooperation between the different vertically spaced contact portions thereof and the column selecting stops carried by the frame of the machine.

The main purpose of my invention, generally stated, is to overcome these and other difficulties and provide improved, highly efficient and reliable tabulating mechanism in a typewriting machine of the type wherein the carriage in its entirety has a case shifting movement.

To the above and other ends which will hereinafter appear, my invention consists in the features of construction, arrangements of parts and combinations of devices set forth in the following description and particularly pointed out in the appended claims.

In the drawings, wherein like reference characters designate corresponding parts in the different views:

Fig. 1 is a fragmentary fore and aft vertical sectional view of the rear portion of a No. 10 Remington Noiseless typewriting machine equipped with the devices of my invention.

Fig. 2 is a fragmentary fore and aft vertical sectional view of a portion of the case shifting mechanism.

Fig. 3 is a fragmentary top plan view of the

rear portion of the machine shown in Fig. 1, the view showing certain parts broken away and other parts omitted.

Fig. 4 is an enlarged, transverse vertical sectional view of a portion of the tabulating mechanism, the view being taken on line 4—4 of Fig. 3 and viewed in the direction of the arrows at said line.

Fig. 5 is an enlarged fore and aft vertical sectional view taken on line 5—5 of Fig. 4 and viewed in the direction of the arrows at said line.

Fig. 6 is an enlarged horizontal sectional view taken on line 6—6 of Fig. 5 and viewed in the direction of the arrows at said line.

Fig. 7 is an enlarged horizontal sectional view of a detail of the present construction, the view being taken on line 7—7 of Fig. 4 and viewed in the direction of the arrows at said line.

Fig. 8 is an enlarged perspective view of a detail of the tabulator construction.

Fig. 9 is an enlarged horizontal sectional view of a portion of the tabulating and escapement mechanism, the view being taken on line 9—9 of Fig. 1 and viewed in the direction of the arrows at said line.

I have shown my invention embodied in the present instance in a No. 10 Remington Noiseless machine in which the features of the present invention may be readily incorporated with but few changes in the existing structure. However, it is to be understood that my invention is not restricted to embodiment in such machine but may be employed in various other types of typewriting and like machines wherever found available.

I have shown in the accompanying drawings only so much of the usual construction of the No. 10 Remington Noiseless machine as is necessary to arrive at an understanding of my invention in its embodiment therein.

Referring to Figs. 1 and 2 the frame of the machine includes the usual side plates 10 joined by cross members 11, 12 and 13 and the usual rear plate 14. The carriage includes the usual platen 16 carried by carriage end plates 17 secured at opposite ends of a main carriage supporting rail 18. The carriage is mounted for longitudinal letter space travel from side to side of the machine on a case shiftable member or guide rail 20 by crossed anti-friction rollers 21 received in oppositely disposed raceways 22 in said guide rail and companion raceways 23 in the sides of the carriage supporting rail 18.

The entire carriage is mounted for substantially vertical case shifting movement by a case

55

shifting rock shaft 25 pivotally supported at 26 (see Fig. 3) on the frame of the machine. Thus, depending lugs 30 on the guide rail 20 are pivotally connected at 31 to companion crank arms 32 5 carried by the rock shaft 25. The elevated or upper case position of the carriage and case shifting mechanism therefor is shown by the solid lines in Figs. 1 and 2 and in the last mentioned figure the dotted lines illustrate the lower 10 case position of some of the parts.

Referring more particularly to Fig. 2, it will be understood that the case shifting movement of the carriage is effected by rocking the shaft 25 through the usual case shift operating mechanism including a toggle crank 35 pivoted at 36 to an arm 37 extending forwardly from the rock shaft 25. The crank 35 is pivotally connected at 38 to a link 39 which in turn is pivotally connected at 40 to the rear end of an arm 41 pivoted 20 at 42 to the side plate 10 of the machine frame. The forward end of the arm 41 is connected at 43 to a compressible link connection which is of the usual construction to afford a limited amount of resilient compressibility and has been designated as a whole by the reference numeral 44 in Fig. 2. The lower end of the link connection 44 is connected at 45 to a crank arm 46 extending rearwardly from a key lever operated rock shaft 47 which is pivotally mounted at its end portions 30 by means, not shown, to the side plates 10 of the machine frame.

The usual case shifting key levers 48 are operatively connected, one at 49, to the respective crank arms 46 at the end portions of the rock shaft 47, these crank arms being somewhat alike and each of the key levers 48 carries a case shift key 50 at the forward end thereof. The usual case shift locking mechanism is provided on each of the case shift key levers 48, and this mechanism includes a shift lock key 52 carried by an arm 53 pivotally mounted at 54 upon the associated lever 48 and operating against the force of a contractile spring 55. Each arm 53 coacts in the usual manner with a latch member 56 pivoted at 57 to the companion lever 48, and each latch member 56 operates on an associated latch plate 58 mounted at 59 to the side plate 10 and thus acts to releasably hold the levers 48 in their depressed or upper case position in the usual 50 manner.

The illustrated upper case position of the various case shifted parts is limited by an adjustable stop screw 60 carried by the arm 37 and engageable with the head of a screw 61 threaded 55 into the cross member 12 of the machine frame. The lower case position illustrated by the dotted lines in Fig. 2 is limited by the usual toggle stop mechanism including a crank 62 pivotally mounted at 63 to a side plate 10 and pivotally connected at 64 to a depending arm of the toggle crank 35. A forwardly extending arm of the bell crank lever 62 is shifted by a movement of the case shifted parts to their lower case position into engagement with the head of an adjustable 60 stop screw 65 also carried by a side plate 10. A contractile spring 66 is provided between the bell crank lever 62 and the head of the pivot screw 42.

Referring to Fig. 3, it may be seen that the 70 carriage is impelled in a letter feed direction by the usual spring drum 70 carried by a bracket 71 mounted on the cross member 12 of the frame of the machine. A pull band 72 extends from the spring drum 70 to a connecting bracket 73 carried by the right-hand carriage end plate 17.

As may be seen in Figs. 1 and 9, the carriage movement in the letter fed direction is normally controlled by the usual form of escapement devices including a releasable feed rack 75 pivotally mounted on the carriage supporting rail 18 to 5 normally engage a feed pinion 76 fixedly secured at the upper end of a substantially vertically disposed feed shaft 77. The upper end of the feed shaft 77 is rotatively supported by a socket bearing 78 (see Fig. 3) pivotally mounted at 79 10 in a bracket 80 secured to the carriage rail 20 at 81.

As best shown in Fig. 9, an escapement wheel 82 is operatively connected near the lower end of the feed shaft 77 to rotate therewith and is 15 rotatively supported by the usual tabulating brake drum 83 in a bracket 84 mounted at 85 on the cross member 12 of the machine frame. The connection between the feed shaft 77 and the escapement wheel 82 is herein shown as comprising 20 the usual anti-friction bearing balls 86 received in oppositely disposed longitudinal grooves or ways in the hub portion of the escapement wheel 82 and in corresponding grooves or ways in the escapement feed shaft 77. 25

The usual form of dog rocker assembly is employed to cooperate with the escapement wheel 82, and comprises in the present instance a dog rocker 88 having down turned lateral end portions recessed to receive coned ends of pivot 30 screws 89 carried by respective spaced arms 90 extending rearwardly and downwardly from the bracket 84. A forwardly extending arm 91 of the dog rocker 88 carries on the upper side thereof a holding dog 92 pivotally mounted thereon 35 at 93 and biased to its normal position by a spring 94 to engage the teeth of the escapement wheel 82. The holding dog 92 is also mounted on the pivot 93 for a slight sliding movement 40 against the force of a spring 95.

A stepping dog 96 which is normally out of engagement with the teeth of the escapement wheel 82 is pivoted at 97 on the lower side of the arm 91 of the dog rocker to receive a movement against the force of the same spring 94 that is 45 also connected to the holding dog 92. The movement of the stepping dog 96 against the force of the spring 94 is limited by a stop arm 98 which enters a bifurcation in the tail of the stepping dog 96. The stop arm 98 is mounted by a pivot 50, (not shown) which is adjustably secured to a rearwardly extending portion of the dog rocker 88.

The dog rocker 88 is biased to its normal position by a spring 99 to engage a stop screw 100 55 with the edge of the associated bracket 90 and thereby limit the return movement of the dog rocker to the normal position. The dog rocker is rocked about the pivot screws 89 upon the actuation of any one of the printing keys or the 60 space bar by the usual means, not shown.

In order to release the carriage for tabulating, the mechanism usually employed in the No. 10 Remington Noiseless machine is used in the present instance to release the holding dog 92 65 from the teeth of the escapement wheel 82 and also to apply the usual friction brake to the brake drum 83. Thus upon reference to Figs. 1 and 9, it will be seen that in the present instance, a bell crank lever 105 is pivotally mounted at 106 70 on a depending bracket 107 which is fixedly attached to the cross member 13 of the machine frame by the same screws 85 that are provided to hold the bracket 84. Referring to Fig. 9, it will be clear that when the rearwardly extending arm 75

of the bell crank lever 105 is raised, the upright arm thereof operates against the tail piece 108 of the holding dog 92 to rock said dog out of engagement with the teeth of the escapement wheel 82 and thereby free the carriage from control of the escapement mechanism for movement from right to left under the power exerted by the spring drum 70.

The friction braking means, which is provided to retard the movement of the carriage when the holding dog 92 is thus released, comprises a frictional brake member 110 pivotally mounted at 111 on the bracket 84. A leaf spring 112 attached to the brake member 110 at 113 coacts with an adjustable stop screw 114 threaded into the bracket 84 and is arranged to press the brake member 110 towards the brake drum 83 and to a position where a shoe portion 110^a engages the periphery of the brake drum.

The application of the braking member 110 at a tabulating operation is effected in the following manner. A contractile spring 116 is connected to the rearwardly directed arm of the bell crank lever 105 and to a cross member 117 of the rear cross plate of machine frame, and the tension of this spring is sufficient to overcome the tension of the spring 112 and normally hold the brake member 110 out of effective engagement with the brake drum 83. This is brought about by the engagement of the upright arm of the bell crank lever 105 with an adjustable contact screw 118 carried by an extension 119 of the brake member 110. It will now be understood that when the rearwardly directed arm of the bell crank lever 105 is operated upwardly during a tabulating operation, as will be hereinafter more fully described, the holding dog 92 will be released from the teeth of the escapement wheel 82 and the brake member 110 will be sprung pressed into effective engagement with the brake drum 83.

Although I have described in detail the case shifting mechanism, the carriage escapement mechanism and the mechanism by which the carriage is released from control of the escapement mechanism on the actuation of the tabulator which are ordinarily employed in the No. 10 Remington Noiseless machine, it should be understood that so far as the present invention is concerned any suitable devices may be employed in lieu of these parts.

The tabulating mechanism in the present instance is of the column selecting type and includes the usual arrangement of a plurality of column stops adjustably mounted in spaced relationship longitudinally of the carriage and each provided with a contact portion which is differently disposed than the contact portion of all of the other column stops so that each contact portion travels in a different path from all of the others. The column stops cooperate with key controlled column selecting stops each disposed to coact with only one of the column stops.

In the present type of machine, wherein the entire carriage, including the column stops, has a case shifting movement, I propose to mount the cooperative column selecting stops to receive a case shifting movement with the carriage in order to retain the proper selective cooperation between the column selecting stops and the respective column stops. I further propose, nevertheless, to provide individual key operated controlling means mounted on the frame of the machine for each of the column selecting stops, which controlling means are operative to control

the companion column selecting stop regardless of the case shifted position thereof. Thus, the carriage carries a rack or column stop bar 125 mounted longitudinally between the upper rear ends of the carriage end plates 17 and adjustably secured thereto. As may be seen in Fig. 3, a similar mounting means is provided for each end of the stop bar 125, one of which mounting means will be described with reference to Fig. 7, it being understood that such description will apply to both.

The upper and rearward portion of each carriage end plate 17 is provided with a boss 127 having a screw 128 threaded therein. The inwardly protruding end of the screw 128 passes through a fore and aft horizontally disposed slot 128^a in an L-shaped bracket 129 and a nut 130 is threaded on the screw 128 to retain the bracket 129 in place against the usual paper table supporting bracket 131. This last mentioned bracket also has an opening receiving freely therethrough the screw 128 and bearing against the inside surface of the boss 127. The other arm of the bracket 129 also has a horizontally disposed slotted opening that extends in the direction of the length of the column stop bar and receives the stem of a headed screw 132 threaded into an opening in the stop bar 125.

The outwardly protruding end of the screw 128 passes through a spacing washer 133 and through a horizontally disposed fore and aft slot in a second L-shaped bracket 134, and the bracket 134 is held in place by a nut 135 threaded on the screw 128 and bearing against the outside surface of the washer 133. The other arm of the bracket 134 is also provided with a slotted opening that receives the stem of a headed screw 136 threaded into an opening in the stop bar 125.

It will now be clear that the horizontal slots in the brackets 129 and 134 afford a slight amount of horizontal adjustment of the rack bar 125 relative to the carriage end plate 17, and likewise the slots receiving these screws 132 and 136 respectively afford a slight amount of longitudinal adjustment of the rack bar 125 relative to the end plate 17. In order to facilitate this longitudinal adjustment of the stop bar 125 and to hold it against accidental displacement from its adjusted position, an adjusting screw 137 is provided which is threaded through a tapped opening in the bracket 134 and engages at its inner end an end of the stop bar 125.

Referring to Fig. 3, it will be seen that the stop bar 125 is provided with teeth 138 in both the front and rear vertical faces thereof which are spaced a letter space distance apart. The stop bar 125 carries in the interdental spaces thereof a plurality of tabulator or column stops each designated as a whole by the reference numeral 140. There are five of such stops employed in the present instance which may be adjusted to the desired spaced relationship along the bar 125.

These column stops 140 are all similar in construction, except as hereinafter pointed out. Each stop, as may be seen in Fig. 5, comprises a generally U-shaped piece 141 adapted to straddle or fit over the stop bar 125, and each of the vertical legs of the U-shaped piece 141 is provided with two webs 141^a which are spaced to fit companion interdental spaces in the stop bar 125. A finger piece 142 is riveted in an opening in the top of the U-shaped piece 141, and the

downwardly projecting end of the finger piece 142 is adapted to engage the upper surface of the stop bar 125 and thereby accurately determine the vertical position of the column stop 140 on the stop bar 125.

The column stops 140 are in the present instance employed for column selecting and are respectively numbered "1", "2", "3", "4" and "5" as may be seen in Fig. 3 and are arranged in this order from left to right. Each of the stops 140 is accordingly provided with a lug or contact portion 143 which extends rearwardly from the rear vertical leg of the U-shaped piece 141. However, the contact portion 143 of each of the stops 140 is spaced at a relatively different point along the rear vertical surface of the piece 141. That is, the contact portion 143 on the extreme left-hand stop "1" is at the top of the piece 141 while the contact portion 143 on the extreme right-hand column stop "5" is at the bottom of the piece 141 and the contact portions of the intermediate stops are spaced at relatively different intermediate levels. Therefore, the contact portion 143 on each column stop travels in a different path from the paths of the contact portions on the remaining stops.

As previously stated, the column selecting stops coacting with the stops 140 on the carriage are mounted for case shifting movement with the carriage. As best shown in Figs. 1 and 4, the column selecting stops and certain of the controlling means therefor are, in the present instance, mounted in a frame that receives a case shifting movement with the carriage and is received between and above two parallel guide members or vertical webs 146 and 147 which are integral with and extend rearward and upward from the cross member 12 of the machine frame. A fixed guide plate 148 similar to that employed in Remington Noiseless machines to resist the pressure of the type bars on the platen and carriage is fixedly secured to the members 146 and 147 by headed screws 149 that are threaded into tapped openings in inwardly extending portions 146^a and 147^a of the webs 146 and 147 respectively.

This guide plate 148 cooperates with the usual means that coat with a carriage thrust rail 150 which is secured at its opposite end portion 50 by screws 151 to the respective carriage end plates 17. Thus, as may be seen in Figs. 5 and 6, a bracket 152 extends beneath the thrust rail 150 and carries two spaced rollers 153 pivotally mounted thereon to engage the front edge of the rail 150. Secured to the front end portion of the bracket 152 is a retaining strip 154 having U-shaped lugs 154^a which embrace the front edge portion of the rail 150. A down turned arm or foot piece at the rear of the bracket 60 152 is apertured to receive the stem of a headed screw 155 extending through an opening therein and through an elongated vertical slot 148^a in the guide plate 148. The stem of the screw 155 also passes through an opening in a retaining strip 156 which is secured thereon by a nut 157 threaded on a reduced diameter end portion of the screw 155.

The retaining strip 156 is sufficiently wide to overlie the walls of the vertical slot in the guide plate 148, as may be seen in Fig. 4, and a narrower upper end portion 156^a of the retaining strip is bent forward to extend through the slot 148^a in the guide plate 148 and to contact without binding the upper surface of the thrust rail 75 150. The rear edge of the thrust rail 150 en-

gages the guide plate 148 to resist any rearward displacement of the carriage, and the rollers 153 by engaging the forward edge of the thrust rail 150 resist any forward displacement thereof in a like manner. In both instances, however, the thrust rail is free to travel with the carriage without any appreciable resistance from the members which coat therewith. It will also be clear that when the carriage receives a case shifting movement this carriage thrust mechanism including the brackets 152 and 156 and the thrust rail 150 have a corresponding case shifting movement permitted by the vertical slot 148^a in the guide 10 148 but these parts except the thrust rail 150, are retained against a letter space feed movement by 15 the walls of this slot 148^a in the guide plate.

In the present instance, the guide plate 148 is modified to carry a mounting means or guide for a case shifting carrier or frame in which the column selecting stops and certain of the actuating devices therefor are mounted. Thus, referring to Fig. 8, it may be seen that a carrier guide member or plate 160 is provided in the rear of the guide plate 148 and disposed substantially parallel therewith and is accordingly disposed in alignment with the substantially vertical case shifting movement of the carriage.

The plate 160 is held in this spaced relation at the rear of the guide plate 148 by headed screws 161 (Figs. 6 and 8) which pass through openings in the upper end of the plate 160 and through openings in an interposed part of a guide shoe 162 and are threaded into the guide plate 148. The lower end of the plate 160 is retained in a similar manner by screws 163 which pass through openings in the lower end thereof and through openings in a spacer 164 and the foot piece of a U-shaped bracket 165 and are threaded into openings in the lower portion of the guide plate 148. The spacer 164 together with the bracket 165 have a combined thickness which is equal to that of the guide shoe 162 so that the plate 160 is held in exact parallel relation with the guide plate 148. The function of the guide shoe 162 and bracket 165 will be described in detail later.

The width of the guide plate 160 is sufficient to overlap the spacer 164 and the base portion of the guide shoe 162, and in the present instance this overlapping edge portion of the guide plate forms a guide for the case shifting frame of the column selecting stops. Said frame in the present instance includes two side plates 166 and 167 (Figs. 6 and 8) having longitudinal grooves receiving the overlying edge portions of the plate 160. The plates 166 and 167 are connected by a separating plate 168 and by screws 169. The connected plates 166 and 167 are thus guided for movement along the plate 160 in exact alignment with the case shifting movement of the carriage.

In the present instance, a substantially horizontally disposed box-like housing is provided above the ends of the side plates 166 and 167 for enclosing the column selecting stops which coat with the column stops 140 on the carriage. Thus referring to Figs. 4, 5 and 6, it may be seen that a three sided housing open at the front thereof is mounted by means of an angle bracket 171 (see Fig. 4) upon the side plate 166, the angle bracket 171 being secured to housing 170 by screws 172 threaded into the lower side of said 70 housing whereas screws 173 are threaded into the side plate 166 to secure the bracket 171 thereto. As may be seen in Fig. 5, a depending rear vertical portion 170^a of the housing member 170 is also attached to the side plates 166 and 167 by 75

respective screws 174 threaded into openings in the rear edges thereof.

The frame for the column selecting stops thus far described, including the end plates 166, 167 and the housing 170 is connected for case shifting movement, in the present instance with the case shifting carriage guide rail 20. Referring to Figs. 4 and 5, it may be seen that this connection is provided by a rearwardly extending arm 175 having a laterally bent portion thereof fixedly secured to the lower surface of the carriage guide rail 20 by screws 176. The rear end of the arm 175 is fixedly though adjustably secured by a bolt 177 to the lower end of a connecting link 178 which is secured at its upper end by a screw 179 to the side plate 166. The bolt 177 is received in a substantially vertical slot in the arm 178 and is held in its adjusted position therein by a clamping nut 177a, whereby the arms 175 and link 178 may be fixedly connected at relatively different positions in order to adjust the case shifted positions of the frame which carries the column selecting stops.

As shown in Figs. 4, 5 and 6 a plurality of pivoted horizontally disposed, column selecting stops 180 are mounted in spaced relationship upon a substantially vertical pivot screw 181 which passes through an opening in the upper horizontal portion of the housing 170 and a reduced diameter lower end thereof is threaded into the lower portion of said housing. The pivoted stop members 180 are separated from each other and from the housing 170 by respective forwardly extending webs of a spacing member 182. Referring to Fig. 35, it will be seen that the upper pivoted column selecting stop 180 is positioned in alignment with the path of travel of the contact portion 143 of the column stop 140 which is numbered "1", and the remaining column selecting stops 180 are so spaced that each aligns with the path of travel of the contact portion 143 of one of the remaining column stops 140 which are respectively numbered from two to five.

All of the column selecting stops 180 may be 45 of identical size and shape as shown in Fig. 6 wherein it may be seen that each stop 180 is provided with an extending tail portion 180a which is engaged by a companion expansion spring 184. The springs 184 are received in respective horizontal openings in the guide member 182, and the rearward ends thereof engage a spacing plate 185 secured to the rear vertical portion of the housing 170 as by spot welding.

Referring to Fig. 4, it will be seen that the 55 springs 184 are arranged from bottom to top of the housing 170 at progressively greater distances from the axis of the pivot screw 181 which accordingly results in a progressively greater effective turning force on the respective stops 180 for purposes to be later described. As indicated in Fig. 6, the springs 184 act on their respective stops 180 to normally engage a rearwardly projecting lug portion 180b with stop strips 186 which are attached, as by spot welding, to the rear 60 vertical edge of the housing 170.

It will be seen in Fig. 5, that each of the stops 180 is normally held by its companion spring 184 in a position which is out of the path of travel of the contact portion 143 of the companion column stop 140. In the present instance, there are individual, key actuated, controlling means for operating each of the stops 180 forwardly to a position where it coacts with the contact portion 143 of the associated column stop 140.

75 Referring to Figs. 4 and 5, it will be seen that

there is a vertically disposed actuating lever 190 for each of the stops 180, said levers 190 being mounted in spaced parallel relation between the side plates 166 and 167 of the case shiftable tabulator frame. The control levers 190 are all mounted on a pivot pin 191 which passes through an opening in the side plate 166 and is provided with a reduced diameter end which is threaded into the side plate 167. Spacing washers 192 are provided for separating the actuating levers 190 from each other and for separating the end levers from the side plates 166 and 167.

As may be seen in Fig. 5, the upper end portions of the actuating levers 190 which are all substantially U-shaped are received within the 15 housing 170 and extend to different heights so that the upper forwardly projecting end of each lever aligns and coacts with only one of the column selecting stops 180. Referring to Fig. 6, it 20 may be seen that the upper engaging end of each of the actuating levers 190 is wedge shaped to enter a companion one of a series of notches 180c in the companion stop 180.

It will be clear that due to the horizontally spaced arrangement of the upper ends of the levers 190, the upper end of each lever will engage the companion stop 180 at a relatively different distance from the pivot 181. Accordingly, the springs 184 are arranged to act on the associated stops 180 at varying distances from the pivot 181 as previously described to compensate for the varying effective turning force exerted by each of the levers 190 on the companion stop due to its relatively different point of engagement therewith.

It will be seen from Fig. 6 that each of the column selecting stops 180 is provided in the forward edge thereof with an engaging notch 180e arranged adjacent to a cam portion 180f and intermediate the contact edges 180g and 180h for purposes which will hereinafter more clearly appear.

The levers 190, being pivotally mounted on the case shiftable tabulator frame obviously have a case shifting movement with the stops 180 also carried by said frame, and accordingly means are herein provided for operatively connecting the lower end of the levers 190 with key operated key controlled actuating means mounted on the machine frame regardless of the case shifted position of the shifting tabulator frame.

The previously mentioned bracket 165 (see Fig. 8), which is mounted on the fixed guide plate 148 and accordingly does not have a case shifting movement, is provided with rearwardly and downwardly extending spaced arms 165a which carry a pivot screw 194 as shown in Figs. 4 and 5. The pivot 194 passes freely through an opening in one arm 165a and is provided with a reduced diameter threaded end portion that is threaded into a tapped opening in the other arm of the bracket and is retained in place by a nut 195 threaded on the protruding end of the pivot. There is a bell crank lever 197 for each of the levers 190 mounted on the pivot screw 194 and retained in spaced parallel relation thereon by spacing washers 198.

The upwardly extending arm of each of the pivot bell crank levers 197 is pivotally connected 70 at 199 to an associated link 200, which link is in turn connected at 201 to the lower end of the companion one of the actuating levers 190. The forwardly extending arm of each of the bell crank levers 197 is pivotally connected at 204 to the 75

upper end of a companion one of a plurality of substantially vertically disposed slide members 205. Each of the slide members 205 is provided with a loop portion 205^a which affords a slight 5 resiliency between the pivot 204 in the body portion thereof. A contractile spring 206 is connected to a forwardly extending portion 205^b of each of the slide members 205, and the lower ends of all of the springs 206 are connected to an 10 anchoring strip 207 which is hooked around an anchor screw 208 which passes freely through an opening in the vertical web 146 and is threaded into a tapped opening in the opposite vertical web 147. 15 Referring to Figs. 1 and 9, it may be seen that the lower end of each of the vertical slide members 205 is received in a companion slot in a guide member 210. The guide member 210 is mounted by screws 211 on a bracket 212 which is 20 in turn mounted by screws 213 on the lower cross member 117 of the machine frame. The slide members 205 are all retained in their respective slots in the guide member 210 by a retaining strip 214 which is substantially U-shaped to pass 25 around the front edges of all the members 205 and is attached to the guide member 210 by screws 215.

Each of the vertically disposed slides 205 is provided with a forwardly extending toe portion 30 205^c which engages the lower side of a universal arm 217 which is pivotally carried at one side by the same pivot 106 and bracket 107 that pivotally carries the crank arm 105. The other side of the universal arm 217 is pivotally mounted 35 at 218 on a depending bracket 219 which is attached at 220 (see Fig. 9) to the central portion of the bracket 107. The rearward end of the universal arm 217 engages the lower side of the rearward end of the crank arm 105, and accordingly 40 an upward movement of any one of the slides 205 will rock the arm 105 to release the holding dog 92 from the teeth of the escapement wheel 82 in the manner previously described.

In the present instance a key lever operating 45 means is provided for effecting a longitudinal upward movement of each of the slide members 205. Thus, a key lever arm 225 for each of the slides 205 is pivotally mounted intermediate its ends on a shaft 226 which is retained by screws 227 between spaced forwardly extending arms 228 carried by the cross member 117. The extreme rearward end of each of the arms 225 enters the companion slot in the guide member 210 and an upper rounded edge thereof engages the lower 50 edge of the companion slide member 205.

Referring to Figs. 1 and 2, it may be seen that a key lever 230 is pivotally mounted at 231 on each of the arms 225, and the position of the levers 230 relative to the companion arms 225 55 may be adjusted by a screw 231 threaded through an opening in a horizontally bent portion 232 at the forward end of each of the arms 225. The upper end of the screw 231 engages the lower edge of the companion lever 230 to arrest the lever 60 at various positions relative to the companion arm, and the adjusted position thereof may be retained by a lock nut 233 threaded on the screw 231.

The forward end of each of the key levers 230 65 extends upwardly as shown in Fig. 2 and a stop lug 235 is provided which normally engages a stop strip 236 secured to the lower surface of a guide comb 237 which is attached at its respective end portion at 238 to the side plates 10 of 70 the machine frame. A suitable key 240 is secured

to the extreme upper end of each of the levers 230, and each key 240 may be provided with a suitable legend marked thereon such as shown in Fig. 3.

In operating the tabulator mechanism of the 5 present invention, it will be clear that a depression of any one of the five tabulating keys 240 will operate through its key levers 230 and arms 225 to effect a vertical upward movement of the 10 companion operating slide 205. The upward 15 movement of the slide 205 releases the carriage for movement from right to left by releasing the holding dog 92 from the teeth of the escapement wheel 82 through the universal arm 217 and crank arm 105, as previously described. The 20 upward movement of the slide 205 also operates its companion bell crank lever 197 in a clockwise direction as viewed in Figs. 1 and 5, which in turn operates through its link 200 to effect a counter-clockwise operation of the associated 25 pivoted actuating lever 190.

The operation of the lever 190 rocks the companion column selecting stop 180 forwardly about the pivot 181 to a position wherein the contact portion 143 of one of the column stops 140, which 25 is at the same level as the actuated column selecting stop 180, engages the left-hand wall of the notch 180^c thereof to arrest the carriage in its free movement from right to left. Referring to Figs. 6 and 8, it will be seen that a rearwardly 30 extending portion 162^a of the guide shoe 162 contacts with the left-hand surface of the side plate 167 and thereby supports and resists displacement of the frame for the column selecting stops in a direction of letter space movement upon arrest of the carriage. 35

In the operation of the present tabulating mechanism, the carriage as it approaches the selected position of arrest causes the rear end portion of the contact portion 143 of the column stop 140 to engage the contact edge 180^c of the companion column selecting stop 180 which is in its forward projected position and thereby exerts a slight camming action thereon and accordingly effects a slight rearward movement of the 40 column selecting stop about its pivot. When the carriage is arrested by the engagement of the contact portion 143 with the left-hand wall of the notch 180^c, the stop member 180 again moves forwardly to its extreme projected position so that the right-hand wall of the notch 180^c is in the path of travel of the stop contact 143 in a left-hand direction, and thereby acts to prevent any rebound of the carriage from its arrested position. 50

The previously described slight rearward turning motion of the stop member 180 as effected by the contact portion 143 in approaching its arrested position may either be allowed by the upward movement of the companion tabulating key 240 against a force exerted by the operator thereon, or it may be allowed if the operator forcefully retains the tabulating key in its depressed position by a slight compression of the loop portion 205^a of the companion operating slide 205. 55

It will also be clear that the present tabulating mechanism may be employed to properly position the carriage when it is manually returned from left to right, during which operation, the contact portion 143 will engage the sloping edge 70 180^c of the stop 180 to effect a rearward movement of the companion stop 180. This rearward movement allows the contact portion 143 to enter the notch 180^c of the companion stop 180 and arrest the right-hand movement of the carriage 75

5 by engaging the right-hand wall of the notch. In this case, the rearward movement of the column selecting stop 180 may also be effected either by an upward movement of the companion tabulating keys 240 or by a compression of the loop portion 205^a of the companion slide 205.

10 Referring to Figs. 3, 5 and 6, it may be seen that the housing 170 which holds the stop members 180 is provided with a substantially U-shaped cover plate 245 secured thereto by screws 246 threaded into the edge portion of the housing 170. The forward side of the cover plate 245 is provided with an opening to allow the forward projecting operation of the column selecting stops 180. As may be seen in Fig. 5, the cover plate 245 is provided with a forwardly extending portion 248 at the upper edge thereof, which portion 248, as may be seen in Fig. 3, is bifurcated to form a guide to aid in properly positioning the 15 column stops 140 on the stop bar 125. Thus, the carriage may be manually operated to the desired position of arrest for each of the tabulating keys, and the associated column stop 140 may then be inserted in the interdental space of the stop bar 20 25 125 through the guide formed by the bifurcation in the forward extension 248, thus insuring that the carriage will be arrested at the desired position upon subsequent operation of the tabulating keys.

30 An enclosure is also provided for the portion of the present tabulating mechanism which is mounted between the vertical frame webs 146 and 147 by a cover plate 250 which is held in rearward spaced relation thereto by spacing 35 strips 251 which form rearward extensions of the webs 146 and 147 respectively. The cover plate 250 is secured by elongated headed screws 252 passing through openings therein and through openings in the respective spacing strips 251 and 40 threaded into the webs 146 and 147.

45 In the present tabulator construction, it will be clear that the actuating levers 190 which are mounted on the tabulator frame for case shifting movement with the carriage are each connected with the companion bell crank lever 197 of the key operated mechanism mounted on the frame of the machine by respective links 200 which move during a case shifting operation through a central position which is at right angles to the line of case shifting movement of the 50 carriage and tabulator frame. Accordingly, there is no movement of the actuating levers 190, or the column selecting stops 180 about their pivots, effected by a case shifting movement of the carriage and tabulator frame relative to the key controlling tabulator mechanism. Furthermore, it will be clear that due to this arrangement of the links 200, the key operated controlling mechanism can operate the actuating levers 190 and the stop 180 with equal facility regardless of the 55 case shifted positions thereof.

60 It will be seen that I have thus provided an improved, highly efficient and reliable tabulator mechanism and key operated controlling mechanism therefor in a typewriting machine of the type wherein the carriage in its entirety has a case shifting movement relative to the key operated controlling mechanism. In the specific form shown herein, the tabulating mechanism is 65 of the column selecting type wherein the column stops mounted on the carriage have contact portions which are each disposed at a relatively different position in the line of case shifting movement of the carriage, and accordingly the column 70 selecting stops cooperating with the column 75

stops on the carriage are mounted for a case shifting movement therewith in order that the relation between the column stops and the column selecting stops will always remain the same irrespective of the case positions of the carriage. 5 The key operated controlling mechanism which is mounted on the frame of the machine is operable in the usual manner to release the carriage for free movement from right to left, and means have been provided for operating each of the 10 column selecting stops to a position for arresting the carriage at a predetermined point upon actuation of the companion tabulator key lever regardless of the case shifted position of the carriage and the column selecting stops which are 15 mounted for case shifting movement therewith.

20 Various changes may be made in the construction, and certain features thereof may be omitted, without departing from my invention as it is defined in the accompanying claims.

25 What I claim as new and desire to secure by Letters Patent is:

1. In a typewriting or like machine, the combination of a case shiftable carriage, tabulator stops carried thereby and shiftable therewith in the 25 case shifting movements of the carriage, tabulator keys on the frame of the machine, tabulator stops controlled by said keys, means for shifting said key controlled tabulator stops with the carriage in the case shifting movements of the 30 latter, and means for simultaneously adjusting the case shifted position of all of said key controlled tabulator stops relative to the carriage.

35 2. In a typewriting or like machine, the combination of a case shiftable carriage, column stops 35 carried thereby and shiftable therewith in the case shifting movements of the carriage, each of said column stops having a contact face that has a path of movement that differs from the path of movement of the contact faces of the 40 other column stops, tabulator keys on the frame of the machine, column selecting stops controlled by said keys, each column selecting stop cooperating with but a single column stop, means for shifting said key controlled column selecting 45 stops with the carriage in the case shifting movements of the latter, and means for simultaneously adjusting the shifted position of all said column selecting stops relative to the carriage.

50 3. In a typewriting or like machine, the combination of a case shiftable carriage, tabulator stops carried thereby and shiftable therewith in the case shifting movements of the carriage, tabulator keys on the frame of the machine, tabulator stops controlled by said keys, a tabulator 55 stop frame shiftable mounted on the frame of the machine and in which said key controlled stops are mounted for movement into and out of cooperation with said first mentioned tabulator stops, and means for shifting said tabulator stop frame with the carriage in the case shifting 60 movements of the latter.

65 4. The combination of a carriage mounted for case shifting movement, column stops and cooperative tabulator stops both mounted for case shifting movements with the carriage, tabulator keys mounted in the frame of the machine, and intermediate actuating connections between said tabulator keys and tabulator stops for projecting the latter to effective position and for affording a 70 movement of the tabulator stops relatively to the tabulator keys during the case shifting movements of the tabulator stops with the carriage, the actuating connections between each tabulator key and tabulator stop including a link operative- 75

- ly connected at one end to the companion tabulator stop to be case shifted therewith substantially equal distances each side of a central position wherein the link extends at right angles to the direction of said case shifting movement.
5. The combination of a case shiftable carriage, column stops each having a contact portion that travels with the carriage in a different path from the contact portions of the remaining 10 column stop, column selecting stops each cooperative with but a single one of said column stops, means for causing both the column stops and the column selecting stops to shift with the carriage in the case shifting movements of the latter and 15 thus have the same relationship irrespective of the case position of the carriage, column selecting keys carried by the frame of the machine, and intermediate actuating connections between said column selecting keys and column selecting stops 20 and which afford a relative movement between said column selecting stops and keys during the case shifting movements of the carriage, the intermediate connections between each column selecting key and its associated column selecting 25 stop comprising a pivoted link operatively connected at one end to the companion column selecting stop to be case shifted therewith substantially equal distances each side of a central position wherein the link extends at right angles to the direction of said case shifting movement.
- 30 6. The combination of a case shiftable carriage, escapement mechanism therefor including an escapement wheel and feed dogs therefor mounted on the frame of the machine, coacting tabulator 35 stops both shiftable with the carriage in the case shifting movement of the latter, a tabulator key mounted in the frame of the machine, actuating connections between said tabulator key and one of said tabulator stops for projecting the latter to operative position and for affording a relative 40 shifting movement between said key and the stop controlled thereby during the case shifting movement of the carriage, and means mounted on the frame of the machine and operated by an actuation of the tabulator key for freeing the carriage from control of said feed dogs.
- 45 7. The combination of a case shiftable carriage, escapement mechanism therefor comprising an escapement wheel, feed dogs therefor mounted on the frame of the machine, a feed pinion controlled by said escapement wheel and shiftable with the carriage during the case shifting movements of the latter, carriage releasing means mounted on the frame of the machine for freeing 50 the carriage from control of said feed dogs, two sets of tabulator stops both shiftable with the carriage during the case shifting movements of the latter, tabulator keys mounted in the frame of the machine, means controlled by said keys 55 for controlling the movements of the tabulator stops of one set to effective position and for affording a shifting movement thereof with the carriage during the case shifting movement of the latter, and means controlled by an operation 60 of any of said tabulator keys for actuating said carriage releasing means.
- 65 8. The combination of a case shiftable carriage, escapement mechanism therefor comprising an escapement wheel, feed dogs therefor mounted on the frame of the machine, a feed pinion controlled by said escapement wheel and shiftable with the carriage during the case shifting movements of the latter, carriage releasing means mounted on the frame of the machine for freeing 70 the carriage from control of said feed dogs, a

set of column stops carried by the carriage and each having a contact portion that has a path of travel that is separate and distinct from the path of travel of the contact portion of any of the remainder of said column stops, a set of column selecting stops each cooperative with but a single one of said column stops, said column selecting stops having a shifting movement with the carriage in the case shifting movement of the latter, column selecting keys mounted in the frame 10 of the machine, means controlled by said keys for controlling the movements of the column selecting stops to effective position and for affording a shifting movement thereof with the carriage during the case shifting movement of the latter, and 15 means controlled by an operation of any of said column selecting keys for actuating said carriage releasing means.

9. The combination of a carriage mounted for bodily case shifting movements, escapement 20 mechanism for controlling the letter space movements of the carriage, and tabulating mechanism including a stop carrier mounted for movement with the carriage in its case shifting movements, cooperating stops on said carriage and said carrier, tabulator keys on the frame of the machine, means operable thereby at either case position of the carriage and carrier to release said escapement mechanism and render said cooperating stops effective to arrest the carriage, said means 30 including pivoted links operable equal distances to and beyond a central position at right angles to the line of case shifting movement of the carriage and carrier.

35 10. In a typewriting or like machine, the combination of a carriage having a case shifting movement, and tabulating mechanism therefor comprising column stops mounted to travel with said carriage, coacting tabulator stops, a carrier for said coacting tabulator stops connected for 40 case shifting movement with said carriage, tabulator keys for controlling said coacting tabulator stops, connecting means for moving each of said coacting tabulator stops to effective position upon actuation of the associated tabulator key 45 regardless of the case shifted position of said carrier, and means included in said connecting means for affording resilient relative movement between each of said coacting tabulator stops and the associated tabulator key.

50 11. The combination of a carriage, a tabulator stop having a cam-like contact face and a locking recess below the high point of the cam, a tabulator key for moving said tabulator stop to effective position, operating connections intermediate said key and tabulator stop including resilient means that afford a change in the relationship between said key and stop, and a second stop with which said tabulator stop coacts.

55 12. The combination of a carriage, a tabulator stop having oppositely disposed cam-like contact faces and a locking recess intermediate said faces, a tabulator key for moving said tabulator stop to effective position, operating connections intermediate said key and tabulator stop including resilient means that afford a change in the relationship between said key and stop, and a second stop with which said tabulator stop coacts.

65 13. In a typewriting machine, the combination of a carriage having a bodily case shifting movement, and tabulating mechanism therefor including a stop carrier mounted for case shifting movement with said carriage, a plurality of column stops mounted on said carriage each having a contact portion that travels in a path that dif- 70

fers from the path of travel of the contact portion of any of the remaining column stops, a plurality of cooperating column selecting stops pivotally mounted on said carrier and each cooperative only with one of said column stops, a pivoted operating arm for each of said column selecting stops carried by said carrier, a key con-

trolled actuating member for each of said operating arms carried by the frame of the machine, and means including pivoted connecting links for controlling each of said operating arms by the companion actuating member regardless of the case shifted position of said carrier. 5

LOUIA K. SEAGRAVE.
